DESIGN FOR A COMBINED CASING AND STAND FOR PIPE-CLEANING APPARATUS

John V. O'Brien, Park Ridge, Ill.

Application March 11, 1947, Serial No. 137,510

Term of patent 14 years

(Cl. D9—2)

To all whom it may concern:

Be it known that I, John V. O'Brien, a citizen of the United States and a resident of Park Ridge, county of Cook, and State of Illinois, have invented a new, original, and ornamental Design for a Combined Casing and Stand for Pipe-Cleaning Apparatus, of which the following is a specification, reference being had to the accompanying drawing, forming a part thereof, in which

Fig. 1 is a view in perspective of a combined casing and stand for pipe cleaning apparatus, showing my new design.

Fig. 2 is a top view of the same.

I claim:

The ornamental design for a combined casing and stand for pipe-cleaning apparatus, substantially as shown.

JOHN V. O'BRIEN.
